UNITED STATES PATENT OFFICE.

ADRIEN L. ANDERSON, OF PALO ALTO, CALIFORNIA, ASSIGNOR TO AUGUSTUS TAYLOR,
OF SAN FRANCISCO, CALIFORNIA.

RADIOTELEGRAPHY.

Application filed December 23, 1919. Serial No. 346,913.

To all whom it may concern:

Be it known that I, ADRIEN L. ANDERSON, a citizen of the United States, and a resident of Palo Alto, Santa Clara County, 5 State of California, have invented certain new and useful Improvements in Radiotelegraphy, of which the following is a specification.

The invention relates to radio telegraphy 10 and particularly to radio telegraphy transmission systems.

An object of the invention is to provide a single wave radio signaling system.

The invention possesses other advantageous features, some of which, with the foregoing, will be set forth at length in the following description where I shall outline in full those embodiments of the invention which I have selected for illustration in the 15 drawings accompanying and forming part of the present specification. In said drawings, I have shown several forms of my invention, but it is to be understood that I do not limit myself to such forms, since 20 the invention, as expressed in the claims, may be embodied in other forms.

Referring to said drawings:

Figure 1 is a diagrammatic representation of a radio telegraphy transmission system embodying my invention.

Figure 2 is a diagrammatic representation of a modified form of the system.

Figure 3 is a diagrammatic representation of a modified form of system particularly suitable for high powered stations.

Figure 4 is a further modified form of the invention.

The system includes a suitable source of oscillations, such as the arc 3 which operates in a hydrogen atmosphere and is subjected to a strong, transverse magnetic field, produced by the combined magnet and choke coil 4. The arc is grounded on one side, preferably, the negative, and is connected on the other side to the antenna 5, through the variable inductance or antenna loading coil 6. Direct current is supplied to the arc by the generator 7. Shunted across the arc is a second oscillatory circuit containing an inductance 8 and a capacitance 9, and this circuit is preferably tuned to the same frequency as the antenna circuit.

By increasing the impedance of the shunt

circuit, the arc may be made to oscillate upon the antenna circuit to the practical neglect of the shunt circuit and conversely, by making the impedance of the antenna circuit greater than that of the shunt circuit, the arc will prefer to oscillate on the shunt circuit to the practical neglect of the antenna circuit. Signaling may therefore be readily accomplished by varying the relative impedance of the two circuits and when the arc is oscillating on the shunt circuit, no oscillations are radiated from the antenna circuit.

The variation of the impedance of the antenna circuit is accomplished by opening and closing a resistance circuit which is coupled to the inductance coil 6. This circuit is provided with a signaling key 12, a resistance 13 and a coil 14 by means of which the circuit is coupled to the coil 6. Similarly, the impedance of the shunt circuit is varied by opening and closing the key 15 in the circuit containing the inductance coil 16, coupled to the inductance 8, and the resistance 17. If it is desired to radiate signals from the antenna, the key 12 is opened and the key 15 is closed. Radio frequency current will, for an instant, due to transformer action, flow through the resistance 17, thus causing an energy loss, which has the equivalent effect of inserting the resistance directly into the shunt circuit. This causes the arc to prefer the antenna circuit and it oscillates thereon.

The inclination of the arc to oscillate on the antenna circuit is augmented by the increase in reactance of the shunt circuit due to the detuning of this circuit by the closing of the key 15. The closing of the key 15 causes the arc to oscillate on the antenna circuit by adding resistance to the shunt circuit, and, its oscillations have the frequency of the antenna circuit, since the frequency of oscillations, such as those produced by an arc converter, is the natural frequency of the circuit connected to the arc. Closing of the key 15 decreases the inductance of the coil 8 by mutual inductance and transformer action between it and the coil 16. Thus the natural frequency of the shunt circuit becomes greater than that of the antenna circuit when the key 15 is closed, the amount of increase in frequency

depending upon the inductance of the coil 16 and the coupling between it and the coil 8. Therefore, the shunt circuit no longer has zero reactance to the impressed oscillations, since a series circuit containing an inductance and a capacitance and connected to a source of oscillations, will have zero reactance to said oscillations only when its natural frequency is equal to that of the impressed oscillations, and that its reactance becomes greater as its natural frequency is made greater or less than the frequency of the impressed oscillations; in other words, the closing of the key 15 not only has the effect of adding resistance to the shunt circuit but it also adds reactance to this circuit by detuning it.

It should be noted that when the key 15 is closed current flows through it for only an instant, since its closing adds impedance to the shunt circuit, with the result that the current from the arc is transferred to the antenna circuit; thus, when the contacts 15 open, they open with practically no load upon them. This feature makes it possible to handle a large amount of power with few relay keys.

While I have shown two resistance circuits, one coupled to the antenna loading coil 6 and the other coupled to the shunt circuit inductance 8, it is to be understood, that in some instances, the circuit coupled to the loading coil 6 may be dispensed with, and the system operated by varying the impedance of the shunt circuit only, but in such a system it is often found in practice that there remains in the antenna circuit a residual current when the arc is oscillating on the shunt circuit, and since this residual current is practically eliminated by the use of the two resistance circuit systems, I prefer to use the latter.

The keys 13 and 15 are preferably connected together, either mechanically, as by a rod 18 of insulating material to which a signaling key 19 is secured, or electrically, as shown in Figure 2 wherein the keys 12 and 15 are operated by solenoids 21 and 22 in the circuit of the signaling key 23. Depression of the signaling key, opens the key 12 and closes the key 15, causing the arc to oscillate on the antenna circuit and releasing the signaling key opens the key 15 and closes the key 12, causing the arc to oscillate on the shunt circuit.

One of the advantages of coupling the resistor circuit to the inductance of the oscillatory circuit rather than shunting it around a few turns of the inductance is that this arrangement permits the adjusting of the current and voltage to be handled by the key to values that permit most efficient operation of the key, it being known that there is a certain voltage and a certain current at which a pair of contacts will work most efficiently,

that is, at which minimum sparking occurs.

Another advantage is that the key does not have to be insulated from earth for a very high voltage.

Another advantage obtained by coupling the resistor circuit to the oscillatory circuit is that one pair of contacts may be made to handle the power of a very large transmitter by the arrangement shown in Figure 3, where a number of loops or coils 24-25 are connected respectively in parallel and coupled to the inductances 6 and 8. This arrangement produces a very large current in the key circuit, but this is not detrimental, since the current flows only at the instant of closing of the contacts. The size of the loops is so made that the voltage produced in them is the maximum that the key contacts will stand without detrimental sparking.

The arrangement shown in Figure 3 shows a further simplification of the system in which only one resistor is used which functions alternately in each of the two resistor circuits.

One side of the circuit of the coils 24 is connected to one side of the circuit of the coils 25 by a conductor 26 which is connected to the switch arm 27 of the double contact switch 28 through a resistor 29. Movement of the switch arm to one side closes the circuit of the coils 24 through the resistor and movement of the switch arm to the other side closes the circuit of the coils 25 through the resistor.

In the construction shown in Figure 1, when the key 12 is closed and the key 15 is open, and the arc is oscillating on the shunt circuit and signals are not being radiated from the antenna, there will still be a small current flowing in the antenna, due to the in-phase voltage impressed upon it by the arc. The frequency of this residual current is that of the shunt circuit and not the natural frequency of the detuned antenna circuit and the value of the current will depend upon the impedance that has been inserted in the antenna circuit. Usually, its value is only a small percentage of the total antenna current and its presence is not detrimental, but if desired it may be eliminated or approximately eliminated. A means for accomplishing this result is shown in Figure 2, wherein a resistance 31 is arranged in the antenna circuit. This resistance is shunted by a substantially resistanceless circuit 32 in which is inserted a key 33 which is connected to the signaling key 23 in such manner that depression of the signaling key closes the shunt circuit 32, thereby cutting the resistance out of the antenna circuit. The key 33 is timed so that its opening lags the closing of the key 12.

In high powered stations, where one key is insufficient to handle the load, a plurality of loops inductively connected to each induct-

tance may be employed, and each loop circuit may be provided with a key and means provided for operating the keys in the loops coupled to one inductance simultaneously or 5 substantially so.

In Figure 4 I have shown a plurality of loops 34 coupled to the inductance 8, each loop being provided with a key 35. The keys may be operated mechanically or electrically as hereinbefore set forth. A similar plurality of loops are coupled to the inductance 6 and the keys in said loops are operated by the same means employed for operating the keys 35, but in the opposite direction. 15

I claim:

1. In a radio telegraphy transmission system, a source of oscillations, a radiating circuit containing inductance connected to said 20 source, a circuit containing resistance inductively coupled to said inductance, a non-radiating oscillatory circuit containing inductance shunted around said source, a circuit containing resistance inductively coupled to

25 said last named inductance and means for opening and closing the resistance circuits.

2. In a radio telegraphy transmission system, a source of oscillations, a radiating circuit connected to said source, a non-radiating oscillatory circuit shunted around said source, a circuit inductively coupled to the radiating circuit, a circuit inductively coupled to the non-radiating circuit, a resistor common to both of said inductively coupled circuits and a key for alternately closing one coupled circuit through the resistance and opening the other coupled circuit. 35

3. In a radio telegraphy transmission system, a source of oscillations, a radiating circuit, a non-radiating circuit shunted around said source, a circuit inductively coupled to the radiating circuit, a second circuit inductively coupled to the non-radiating circuit, and means for closing one of the inductively coupled circuits while opening the other, in such manner that the closed circuit includes a substantial amount of resistance. 45

4. In a radio telegraphy transmission sys-

tem, a source of oscillations, a radiating circuit, including an inductance coil, connected 50 to said source, an oscillatory circuit, including an inductance coil, shunted around said source, a circuit including a plurality of loops in parallel coupled to the radiating circuit inductance, a circuit containing a plurality of loops in parallel coupled to the shunt circuit inductance, a key arranged to open one of said latter circuits and close the other and a resistance in the closed circuit. 55

5. In a radio transmitting system having 60 a source of oscillations, a radiating circuit, and a circuit shunted around the source, means for varying the constants of both circuits so as to alter their energy loss characteristics, comprising circuits inductively 65 coupled to the first mentioned circuits, and means for opening and closing said coupled circuits.

6. In a radio transmitting system having 70 an arc for producing oscillations, a radiating circuit, and an absorption circuit, means for causing the arc to oscillate substantially entirely on one or the other of these circuits comprising a circuit inductively coupled to the radiating circuit, a second 75 circuit inductively coupled to the absorption circuit, and means for co-relating the energy loss characteristics of the coupled circuits whereby the characteristic of one is opposite to that of the other. 80

7. In a radio transmitting system having 85 an arc for producing oscillations, a radiating circuit, and an absorption circuit, means for causing the arc to oscillate substantially entirely on one or the other of these circuits, comprising a circuit inductively coupled to the radiating circuit, a second circuit inductively coupled to the absorption circuit, a resistor, and means for connecting the resistor in either of the two coupled 90 circuits, so as to complete that circuit.

In testimony whereof, I have hereunto set my hand at Palo Alto, California, this 15th day of December, 1919.

ADRIEN L. ANDERSON.
